UNITED STATES PATENT OFFICE.

ALVIN N. WOODARD, OF HADLEY, MICHIGAN.

LIFTING-JACK.

SPECIFICATION forming part of Letters Patent No. 240,801, dated April 26, 1881.

Application filed November 10, 1880. (No model.)

To all whom it may concern:

Be it known that I, ALVIN NELSON WOODARD, of Hadley, in the county of Lapeer and State of Michigan, have invented certain new and useful Improvements on Lifting-Jacks; and I do hereby declare that the following is a full, clear, and exact description of the same.

The nature of this invention relates to certain new and useful improvements in that class of devices employed in lifting or raising heavy articles, and which are commonly known as "lifting-jacks."

The object of the invention is to construct a device for the purpose that shall combine strength and power, that is easy of operation, and that can readily be adapted and employed to perform the various functions of a lifting-jack, jack-screw, &c.

The invention consists, first, in the peculiar construction and operation of the cam-lever employed for operating the machine; second, in the peculiar construction and operation of the dogs, in combination with the double-faced rack-bar and the cam-lever; third, in the construction and arrangement of levers for controlling the action of the dogs; and, fourth, in the peculiar construction, arrangement, and combinations of the various parts, all as more fully hereinafter set forth.

In the drawings, Figure 1 is a perspective view. Fig. 2 is an enlarged inside elevation of one of the cheeks. Fig. 3 is an enlarged perspective of the cam-lever head and its seat. Fig. 4 is a vertical central section at right angles to the plane of the cam-lever. Fig. 5 are perspective details of the various pieces composing one of the dogs.

In the accompanying drawings, which form a part of this specification, A represents a rectangular ratchet-bar, the two opposite sides of which have a continuous sunken ratchet partially across their face, leaving a plane margin upon both sides. This bar terminates in a ball, a, at the top, and at the lower end in a T-shaped foot, b.

B B and B' B' are two sets of dogs. The lower set, B, which act upon opposite sides of the bar A, slide in corresponding sockets in the inner faces of the cheeks C C, which form the body of the machine, as hereinafter described. The lower dogs, B, have a lateral

movement or play in their respective sockets, and firmly resist any tendency to other displacement.

c are coil-springs attached at one end to the spring-plate d, and rest in proper sockets back of the dogs, and exert their force against the dogs in such a manner as to press them firmly against the rack-bar, while their elasticity allows the bar to slide upward, but holds the same securely against any downward strain. These dogs are provided upon their rear faces with a loop, e, through which passes a bolt, f, the cut-away portion g of which performs the function of a cam, when the bolt is turned, to withdraw the dog from its engagement with the ratchet-bar. These bolts f pass out through the cheeks, and are connected at their outer ends, upon one side, by a bell-crank lever, D, by means of which the operator can simultaneously throw the dogs in or out of engagement with the ratchet-bar.

The upper dogs, B', are of the same construction as the lower dogs, but have, in addition to them, a vertical reciprocating movement, which is imparted to them by the following devices.

h represents a rectangular frame with an opening large enough to receive the dog and allow of lateral play therein, while the frame 80 is susceptible of a vertical movement between the cheeks.

i represents links provided upon each end with circular heads, which are centrally perforated. One end of each of these links is placed 85 over a pin, j, in the lower portion of each frame h, the body of which is cut away around such pins to receive the circular heads of the links, which fit snugly therein.

A bolt, k, passes through the cheeks and 90 through the loops in the rear of the dogs in such a manner as to perform the same functions as the bolts f of the lower dogs, but so situated as not to interfere with the vertical play of the dogs. These bolts k are also connected together and operated by a bell-crank 95 lever, E.

F represents the actuating-lever, the arms of which are screwed into or otherwise removably secured to the cylindrical lever-head l, 100 from the two sides of which project a central round lug or pin, m, by means of which the

head is properly pivoted or journaled in suitable bearings formed in the inner faces of the cheeks, which are sufficiently cut away to allow of a free oscillating movement being given 5 to the lever. Through the head *l* is formed an opening, *n*, sufficiently large to allow the ratchet-bar *A* a free movement through the same in any position the head may assume. The links *i*, one end of each of which is pivotally secured to the lower portions of the frames *h*, have their lower ends in like manner pivotally secured to the head, as is clearly shown in Figs. 2 and 4 of the drawings.

The cheeks *C C* are both alike, and are rigidly secured together by proper bolts, and are recessed to receive the working parts above described. To avoid the danger of the ratchet-bar binding upon the inner faces of the cheeks, friction-rollers *o* are properly journaled at top 15 and bottom, between which the ratchet-bar moves, said rollers *o* bearing upon the plane margin of the bar, upon either side of the ratchet-teeth. For the same purpose friction-rollers *p* are placed upon the bolts which secure the two cheeks together, such rollers bearing upon the edge of the ratchet-bar, the cheeks being sufficiently cut away to receive them and allow of their free action.

It will be seen that, all the parts being in 20 engagement and free to perform their various functions, one arm of the lever *F* being depressed will cause the links *i* to assume a position at an angle to the vertical, and that in assuming this position the upper dogs are drawn down into their lowest position. By raising the lever to the horizontal the dogs are forced upward by the links, and by reason of the engagement of the dogs with the ratchet-bar the latter must necessarily be raised in 25 the same degree. At this time the lower dogs have engaged with the ratchet-bar and retain it in its elevated position. A continued upward movement of the same lever will cause the links to draw down the upper dogs and 30 make a fresh engagement with the ratchet-bar, this oscillating movement of the lever being continued until the ratchet-bar has been raised the entire length of its ratchet, or the article to which it is secured is elevated to the height 35 desired.

It will be seen, in the operation above described, that the pins *j*, which pivotally secure the links *i* to the lever and dog-frames, are called upon to perform but one function—that 40 is, to draw the dogs and frames down as the lever is elevated or depressed above or below the horizontal, while the strain in lifting depends upon the links and their resistance to compression. To give slack to the ratchet-bar, the

lower and upper dogs are alternately released 60 and engaged with the ratchet-bar, while the actuating-lever is moved so as to drop the bar one step at a time, or both dogs may be released, when the bar will drop its entire length.

This device can advantageously be employed 65 for the purpose of pulling stumps by hanging the device from any suitable derrick by means of chains passing through the rings *H*, which project above the top of the device and form a part of bolts *I*, rigidly secured to the sides of 70 the cheeks, and project below the same and afford means for securing the device to a proper pedestal, if desired.

What I claim as my invention is—

1. In a lifting-jack, two sets of ratchet-faced 75 dogs, one set actuated by an oscillating lever and adapted to raise the ratchet-bar, and the other set acting as a pawl upon the ratchet-bar to retain it in its elevated position, substantially as described.

2. In a lifting-jack, a set of ratchet-faced dogs, *B*, susceptible of lateral play in the body of the device, in combination with cam-bolts *f*, springs *e*, and bell-crank lever *D*, by means of which both dogs may be simultaneously operated, substantially as set forth.

3. In a lifting-jack, a set of ratchet-faced dogs, *B'*, susceptible of a lateral and a vertical reciprocating movement in the body of the device, in combination with the bolts *k*, by 85 means of which the dogs may be retracted at any point of their vertical movement, substantially as specified.

4. In a lifting-jack, a set of ratchet-faced dogs, *B'*, susceptible of a lateral and a vertical reciprocating movement, substantially as 95 described, in combination with the frames *h*, links *i*, and lever *F*, substantially as and for the purpose set forth.

5. In a lifting-jack, the ratchet-bar *A*, provided with a continuous sunken ratchet upon two opposite faces, with a plane margin at each edge, in combination with friction-rollers which bear upon the four faces of the rack-bar, substantially as set forth.

6. In a lifting-jack, the lever *F*, pivotally secured in the frame, and having two links, *i*, stepped in its upper portion and abutting against the frames which carry the dogs, exerting a pushing force upon said dogs, whereby the ratchet-bar is raised, substantially as and for the purpose specified.

Detroit, Michigan, September 14, 1880.

ALVIN N. WOODARD.
